UNITED STATES PATENT OFFICE.

DANIEL RAYMOND SMITH, OF NEW YORK, N. Y.

SHAVING APPARATUS.

1,255,061.

Specification of Letters Patent. Patented Jan. 29, 1918.

Application filed August 3, 1916. Serial No. 112,808.

To all whom it may concern:

Be it known that I, DANIEL RAYMOND SMITH, a citizen of the United States, residing at New York, in the county of New York and State of New York, have invented new and useful Improvements in Shaving Apparatus, of which the following is a specification.

This invention relates to an apparatus which may be advantageously used for shaving purposes.

The primary object of the invention is to provide an apparatus of the class described which may be conveniently carried in the vest pocket and includes a casing adapted to serve as a handle for a safety razor and is provided with a plurality of longitudinally extending compartments for the reception of a safety razor and a combined brush and soap holder included in the outfit.

Another object of the invention is to provide an apparatus of the class described in which the casing for holding the razor and the combined soap holder and brush is so constructed as to enable access to be had to these articles in a quick and convenient manner.

With these and other objects in view, the invention resides in the novel combination and arrangement of parts which will be hereinafter described and particularly pointed out in the claims.

The preferred embodiment of the invention has been illustrated in the accompanying drawing, although no restriction is necessarily made to the precise details of construction therein shown, as changes, alterations, and modifications, within the scope of the claims may be resorted to when desired.

Like characters of reference denote corresponding parts throughout the several views in the drawing, in which:

Figure 1 is a side elevation of a shaving apparatus constructed in accordance with the invention.

Fig. 2 is a vertical longitudinal section therethrough showing the combined brush and soap holder in elevation.

Fig. 3 is a view similar to Fig. 2 showing the combined brush and soap holder in section.

Fig. 4 is a perspective view of a modified form of the invention, the casing included in the apparatus being shown partly in section.

Fig. 5 is a side elevation partly in section of a modified form of the combined brush and soap holder included in the shaving apparatus.

Referring now to Figs. 1, 2, and 3 in the drawing, the numeral 1 designates a hollow casing formed from any suitable material such as metal, or the like, and is provided with open ends 2 and 3, said casing is oblate in shape in cross section.

Extending transversely of the casing between its ends is a partition 4 which divides the casing into compartments 5 and 6, the compartment 5 being adapted to receive a safety razor 7 which may be of any of the types now in common use.

The open end of the compartment 5 is closed by a flanged cap 8 having an upstanding and threaded stud 9 near one end thereof adapted for connection with the safety razor 7 when said razor is removed from the compartment 5 to enable the casing to serve as a handle therefor.

The compartment 6 is adapted to receive a combined brush and soap holder 10 including a handle 11 and a brush head 12.

The handle 11 is hollow and provided at diametrically opposite points between its ends with longitudinally extending slots 13. A bar 14 extends transversely of the handle 11 and has its ends received in the slots 13 to enable the bar to be moved longitudinally of the handle which it divides into compartments 15 and 16.

A cake of shaving soap 17 is received in the compartment 15 and has an end resting upon the bar 14, so that when a cap 18 has been removed from one end of the handle and the bar 14 moved longitudinally of the handle an end on the cake of soap will be advanced beyond the end of the handle normally closed by the cap 18.

The bristle holding member 19 of the brush head 12 is slidably mounted in the compartment 16 in the handle 11, so that when the cake of soap has been removed from the compartment 15, the bristle holding member may be removed to a position within the handle in which the bristles on the head will be received within the handle to enable the same to serve as a protector therefor.

Through the above described arrangement of the combined brush and soap holder, it will at once be apparent that the parts thereof are so connected that they may be easily

and quickly disconnected for cleaning purposes when the occasion arises.

The end 3 of the casing is closed by a flanged cap 20 which is frictionally engaged 5 with the casing 1 and is provided with a centrally disposed and threaded opening 21 to enable the casing to be connected with a safety razor having a stud for connection with a handle, said opening also insuring the 10 ventilation and draining of the compartment 6.

The construction of the shaving apparatus shown in Fig. 4 in the drawing is similar to that shown in the preferred forms of the 15 invention with the exception that the casing 22 of the apparatus is formed from hingedly connected casing sections 23 and 24 of semi-oblance shape in cross section and held in closed position by caps 25 and 26 identical 20 in construction with the caps 8 and 20 to enable the casing to be connected with the razor associated with the outfit.

The casing 22 like the casing 1 is provided between its ends with a transversely extending 25 partition 27 which is secured to one of the casing sections and like the partition 4 divides the casing into compartments for the reception of the razor and the combined soap holder and brush.

30 The combined brush and soap holder 28 shown in Fig. 5 in the drawing is identical in construction with the combined brush and soap holder shown in the preferred form of the invention with the exception that the bar 35 14 is dispensed with and a partition 29 arranged between the ends of the handle 30 to form compartments 31 and 32 within the handle. The compartment 32 receives the bristle holding member on the brush head 33 40 while the compartment 31 receives a cake of soap 34 connected with a flange 35 on a cap

36 for closing the other end of the compartment 31.

When it is desired to use the shaving apparatus, the cap may be removed from the handle of the combined soap holder and brush after the same has been removed from the casing 1 and the combined soap holder and brush used to produce a lather.

The razor head associated with the casing 50 may be either connected with the stud on the cap at one end of the casing or if the razor head has a stud it may be connected with the cap at the other end of the casing by means of the opening therein, so that the casing 55 will serve as a handle for the razor.

From the above description, it will be seen that a shaving apparatus has been provided in which all parts thereof are so constructed that they may be easily cleaned and that the 60 device as a whole may be quickly assembled for disposition in the vest pocket, the casing of the apparatus being so shaped as to conveniently fit therein.

Having thus described the invention, what 65 is claimed as new, is:

1. In a shaving apparatus, a pair of open ended case sections of semi-oblance shape in cross section and hingedly connected along one edge, a partition between said sections 70 rigidly connected with one of said sections, and flanged caps into which the ends of said sections extend, holding said sections in closed position.

2. In a shaving apparatus, an open ended 75 brush handle of oblance shape in cross section, a flanged cap into which one end of a handle extends, a brush head slidably mounted within said handle, and a follower between said brush head and cap slidably connected 80 with said handle.

DANIEL RAYMOND SMITH.
